BUILDER MOTION

Guy E. Branch, Lowell, Mass., assignor to Abbot Worsted Company, Graniterville, Mass., a corporation of Massachusetts

Application March 17, 1938, Serial No. 196,493

19 Claims. (Cl. 242—43.7)

This invention relates to builder motions such as are used for winding yarn on bobbins and particularly to builder motions used in forming relatively large yarn packages. Some years ago, 5 the trend turned toward the formation of larger yarn packages and this trend received an impetus due to the use of ring spinning instead of cap spinning frames. The change, however, required a change in the builder motion in order to give 10 the required length of wind on these larger bobbins. To this end, the Scaife builder motion was adapted to the purpose, as disclosed in the patent to Chase, No. 2,013,876, granted September 10, 1935. However, various troubles developed in 15 practice such as excessive wear, binding of the parts and frequent breakage, and to remedy this the structure disclosed in the patent to West, No. 1,984,615, granted December 18, 1934, was developed. Later this was improved by the structure 20 shown in the Banfield patent, No. 2,048,590, granted July 21, 1936, where the movement of the ring rail was increased by the use of chains and pulleys of different sizes. This reduced wear and breakage but the cam throw had been reduced to such 25 extent that the slightest irregularity in the face of the cam or the wear in the cam causing back lash in the reciprocating parts, was so magnified that it was extremely difficult to produce a uniformly shaped bobbin.

The general object of my invention is to provide 30 a builder motion which is not open to these objections, which is simple from a mechanical standpoint, and which has been found to be thoroughly effective for the purpose intended. More 35 particularly, my object is to provide a builder motion for a double headed bobbin with a so-called variable wind on which the yarn is wound in successive layers traversing the full length of the bobbin on the longest traverse with a gradual 40 variation in the length of traverse to a minimum traverse about $1\frac{1}{4}$ " less than the full length of the bobbin.

A further object is to provide a builder motion 45 which makes use of only one oscillating lever to transmit motion from the cam and eliminates entirely the screw, rack and gear arrangement found in the modifications of the Scaife builder motion above referred to.

A further object is to provide a structure of 50 this character in which change in the length of the stroke may be readily made and in which the construction is such that all the variation may be made at one end of the stroke.

Other objects will appear in the course of the 55 following description.

My invention is illustrated in the accompanying drawings wherein:

Fig. 1 is a side elevation of a portion of a spinning frame with my builder motion applied thereto.

Fig. 2 is an elevation of one end of the frame showing the means for oscillating the actuating lever.

Fig. 3 is an enlarged section on the line 3—3 of Fig. 1.

Fig. 4 is a fragmentary front elevation of a portion of a spinning frame showing a modified form of builder motion applied thereto.

Referring to these drawings and now more particularly to Figs. 1, 2 and 3, 16 designates a frame element supporting the usual ring rail 11 having thereon the usual rings 12 and travelers 13. The spindle rail 14 carries the usual spindles 15 driven by whirls 16 and carrying the bobbins B. The spindle rail 14 is mounted as usual upon the lifter rods 17 which pass through the fixed guide rail 18. These lifter rods are reciprocated by chains 19 (only one of which is illustrated) passing over fixed guide pulleys 20 and each connected to the vertically adjustable hooks 21 carried by arms 22 attached to the lower ends of the lifter rods, the opposite ends of the chains being attached to a traverse rod 23. So far, as described, the stroke is standard, that is, it is the structure commonly found in builder motions.

Guided in the slot 24 of a frame element 9 is a slide 25 which is attached to the traverse rod 23 in any desired manner. As illustrated, the traverse rod has attached thereto the angle iron 26 and the slide 25 is engaged therewith by an adjusting screw 27. Pivotedly mounted on the slide is an upstanding leveling block 28 having an upwardly and rearwardly inclined face 29. The rear face of the block has a rearwardly extending arm 30 at its lower end and an adjusting screw 31 passes through the arm 30 and bears against the slide 25. Thus the leveling block 28 may be tiltably adjusted.

Extending downward from the frame element 9 are the supports or braces 32 which carry at 45 their lower ends the plate or block 33. Pivotedly mounted upon this block or plate is a lever 34. Preferably the plate or block 33 is vertically slotted at 35 and the pivot 36 of the lever 34 is vertically adjustable in this slot for a purpose to 50 be later stated. Pivotedly connected to the rear end of the lever 34 is a lever 37 which at its upper end is curved rearward or towards the face of the leveling block 28 and carries upon it the roller 38 bearing against the face 29 of this block. 55

The middle portion of this lever 37 is provided with a wear plate 39. For the purpose of oscillating the lever 37, I provide the cam 40 which is mounted upon a shaft 41 carrying the gear wheel 42 driven by a worm 43. This is the standard way of driving the cam 40. Slidely mounted upon a guide 44 is a slide 45 carrying at its forward end the roller 46 against which the peripheral face of the cam 40 bears. This slide 45, as shown in Fig. 3, may be provided with a plurality of internally screw-threaded bores 47 shown as two in number in Fig. 3, and engageable with either one of these bores is the screw-threaded shank 48 of a yoke 49 which carries the roller 50 which bears against the wear plate 39. It will be obvious that as the cam 40 is rotated, the slide 45 will be reciprocated and this will give an oscillative motion to the lever 37, and this lever in turn bearing against the block 28 will give a reciprocating motion to the slide in the usual manner.

The lever 34, which is in the nature of a walking beam, is oscillated by means of a crank arm 51 carried upon a shaft 52 (see Fig. 2) which shaft carries on it the pinion 53 driven by a gear wheel 54 in turn driven through reducing gears 55 and 56 from a worm 57. Shaft 52 is mounted in a bearing 58 on the frame end 59, the shaft being held in place by collars 60. The worm 43 is carried by a shaft 61 upon which is mounted a gear wheel 62 which meshes with a gear wheel 63 mounted on a shaft 64 which carries the belt wheel 65.

While I have illustrated a particular means for driving the gear wheel 54, I do not wish to be limited to this as other means might be used for this purpose.

The crank arm 51 is longitudinally slotted at 66 and is connected to the lever 34 by means of a longitudinally adjustable connecting rod formed in three sections 67, 68 and 69, the section 69 being exteriorly screw-threaded and having engagement with the interior screw-threads on the members 67 and 68. The threads on the screw 69 are reversed in direction so that when this member 69 is turned in one direction, it will cause a contraction of the connecting rod and when turned in the opposite direction, will cause an elongation of the connecting rod. Set nuts 70 may be used to hold the parts 67, 68 and 69 in their adjusted positions.

The general operation of builder motions of this character is well understood and, therefore, no general description of this operation is believed to be necessary, but the parts which particularly constitute my improvement function as follows:

As cam 40 rotates, the slide 45 is reciprocated and gives an oscillating movement to lever 37 in turn reciprocating the chain rail or traverse rail 23 and vertically reciprocating the spindle rail 14 and the spindles. If this were all of the action, the bobbins would be given the same length of stroke at all times and it is to vary the length of the stroke so as to secure a taper of the bobbin 65 at its upper end that I provide means for varying the point of contact or point of application of power to the lever 37. Thus if the lever 37 is lowered relative to the roller 50, the distance between the fulcrum 37^a and the roller 50 will be increased and the stroke of lever 37 will be decreased. If, on the other hand, the lever 37 is raised, the stroke of the lever will be increased.

The variation in the stroke of the lever 37 is secured by the gradual oscillation of the walking beam or supporting lever 34. As the crank 51

rotates, a slow rocking motion is imparted to this lever 34. This alternately raises and lowers the lever 37 which thus gradually diminishes and then increases the distance between its fulcrum 37^a and the point of application of the roller 50. As the distance between the fulcrum 37^a and the roller 50 is increased, less traverse will be given to the slide 25 and less traverse will be given to the bobbins, and as the distance between the fulcrum of lever 37 and the roller 50 is decreased, a greater traverse will be given to the bobbin.

The leverages are so arranged that a maximum traverse of 7" can be secured with a minimum traverse of 5 1/4" with the parts in the general position shown in Fig. 1. If the shank of yoke 49 is shifted into the upper bore or hole 47 in the thrust block, then the traverse is changed to 6" maximum and 4 3/4" minimum. Minor changes in traverse may be obtained by adjusting the pivot 36 for the lever 34 up or down in the slot 35, the length of the connecting rod 67-68-69 being correspondingly changed so that the lever 34 is kept in a horizontal position when the cam 40 is at the center of its stroke. The adjustment of the wrist pin of crank arm 51 and slot 66 nearer to or further from the center of motion of the crank arm determines the amount of movement of lever 34 and thus controls the difference in length between the maximum and minimum stroke, this difference being increased as the throw of the crank is increased and vice versa.

In order that the difference in stroke shall come at the top of the bobbin to produce a taper at the top and fill in at the base, the mechanism is adjusted as follows:

With cam 40 in the center of its stroke, that is, with the cam 40 in a vertical position, yoke 49 is adjusted toward or from the roller 46 by screwing the yoke 49 in or out. The yoke 49 is adjusted until the lever 37 is vertical at this point. When the point of cam 40 bears against the roller 46, the bobbin will be brought to the upward limit of its traverse, which is the position shown in Fig. 1. With the parts in this position, the angle of the inclined face 29 of the leveling block is adjusted by means of screw 31, so that the face 29 is approximately parallel to the face of lever 37 when the crank arm 51 is turned down to give the longest stroke. Now with the cam 40 in the same position and crank arm 51 turned upward to give the shorter stroke, the bobbin will come to the same position, the difference in length of stroke all appearing at the top of the bobbin (with the heel of cam 40 against roller 46) to give the desired taper. Inasmuch as the pivot 37^a of the lever 37 moves through an arc instead of through a plane parallel with the face of the lever, it is necessary to make some compensation for this slight arcuate movement. This requires that there shall be a slight deviation from the parallel between the face of lever 37 and the face 29 of the leveling block 28. This is easily arrived at by trial and error and the face 29 is brought into proper position by adjusting the screw 31. With this setting properly made and the point of cam 40 bearing against the roller 46 on all strokes of intermediate length between the longest and shortest, the bobbin will rise to approximately the same point, that is, a point level with ring 12, which guides the yarn on the bobbin except for a very slight deviation due to the fact that the pivot 37^a moves through an arc rather than through a plane parallel with the face of lever 37. This slight deviation, however, is not enough to be detrimental.

It will be seen that my structure makes use of only one oscillating lever 37 to transmit motion from the cam and that it dispenses entirely with the screw, rack and gear arrangement heretofore used. I believe that the idea of moving the pivot point 37^a of the lever 37 to change the length of stroke has never before been used in builder construction, particularly when combined with the leveling block on the end of the chain rail slide. This structure permits a cam of reasonable size to be used.

While this mechanism has been particularly designed for use with bobbins having a length of 6 or 7" with a 2½" base and a 1½" head, it will be seen that the mechanism may be readily adjusted for bobbins having other sizes.

It will be seen that the yarn is wound on in successive layers traversing the full length of the bobbin on the longest traverse with a gradual variation in the length of traverse to a minimum of about 1¼" less than the full length of the bobbin. The yarn is filled into the base of the bobbin and the variation in traverse all occurs at the top of the bobbin. This builds a bobbin which, when full, is uniform in diameter from the base up to a distance of 1¼" from the top with a taper from this point which narrows down to slightly less in diameter than the top head of the bobbin. The ratio between cam speed and the speed of crank 51 which controls the stroke cycle should vary between 8 to 1 and 15 to 1 for best results on most yarns. Gears 55 and 53 are change gears in the train driving the crank 51. Alteration in the relative sizes of these gears makes it possible to change the ratio of cam speed to speed of crank 51 over a wide range. It is better not to have the cam speed an exact multiple of the speed of crank 51. This is to avoid bringing the termination of strokes of the same length at exactly the same point on successive stroke cycles, which would have a tendency to produce a step effect instead of a taper at the top of the bobbin.

The leveling block or element 28 is of great importance as will appear from the following:— Assume that the face 29 of block 28 is vertical and that lever 37 is vertical, or approximately so, at the center of its stroke. Assume then that the fulcrum or pivot 37^a is raised by raising the pivot 36 of lever 34, thereby producing a longer stroke of the lever 37 by reason of the fact that the roller 50 acts against the lever 37 nearer to its fulcrum 37^a. This increase in stroke will be apparent at both ends of the arc through which the roller 38 swings and the horizontal traverse of block 28 and chain rail 23, and in turn the vertical traverse of the bobbin rail 14 will be extended equally on both ends of the traverse. However, to get the wind which is required, it is necessary to have all the change at the top of the bobbin to produce the desired taper and to have the stroke always terminate at the same point at the base of the bobbin or, in other words, when the point of the cam 40 is engaged with the roller 46. The leveling block 28 accomplishes this purpose when the angle of its face 29 is set as previously described, that is, with the face approximately parallel to the face plate 39 of lever 37, when the cam 40 has its point in engagement with the roller 46. Two actions then take place simultaneously. First, the increasing length of the arc through which roll 38 moves as the stroke lengthens would cause the base of the bobbin to move above the level of ring 12. Second, the angle of the face 29 of block 28 gives

a drop or opposite movement to the bobbin rail as roll 38 moves up the face 29 at this angle. This second action neutralizes the first action, the net result being that on all strokes, the base of the bobbin comes level with the ring 12 and the change in the length of the traverse occurs all at the top of the bobbin to produce the taper thereon. The screw 31, of course, secures this adjustment of the angle of face 29 of the leveling block. The screw 27 is merely used for adjusting the level of bobbin rail in relation to a ring 12 after the builder has been correctly adjusted so that it will bring the termination of all length strokes coincident with the positioning of the cam 40 with its point against the roll 46 and give the correct length of stroke. It will be noted that the face 29 is not exactly parallel with the face plate 39 and it is this slight deviation from absolute parallelism which compensates for the arc traversed by the pivot pin 37^a as before stated.

In making these adjustments, the best procedure is as follows:

First, adjust the throw of the crank 51 for the desired length of taper; second, adjust the fulcrum 36 up or down until correct maximum length of stroke has been obtained, always being careful to make a corresponding change in the length of connecting rod formed by the parts 67, 68 and 69, to keep the lever 34 in a horizontal position at the center of the stroke of crank 51; third, with cam 40 on point, set the angle of face 29 of leveling block 28 so that the bobbin rail 14 will reach the same lower level on both long and short strokes; fourth, level the base of the bobbins to the ring rail by means of the screw 27, and if sufficient adjustment cannot be secured by screw 27, then the lifter rod 17 may be moved up and down in the dogs or arms 22, these lifter rods being vertically adjustable in these dogs or arms.

In Fig. 4, I illustrate a frame with my builder applied thereto, in which the spindle or bobbin rail 14 is stationary instead of being movable, and in which ring rail 11 is mounted on and given a vertical traverse by the lifter rod 17. Except for a certain detailed form of the leveling block and a certain adjustment of this leveling block and except for the fact that the ring rail is movable and the bobbin rail is stationary, the mechanism is substantially the same as that illustrated in Figs. 1 to 3. In the construction illustrated in Fig. 4, the face 29^a of the leveling block 28^a is so adjusted that it inclines toward the left-hand end of the machine, that is, to the left of a vertical plane and an angle of inclination opposite to the angle of inclination of the leveling block 28 in Fig. 1. In Fig. 4, the parts are shown with the heel of cam 40 bearing against the roller 46, thus bringing the ring rail 11 to its lowest point with the relation between the ring rail 11 and the spindle rail 14 the same as in Fig. 1.

Since the taper at the top of the bobbin is now obtained by the action of the traversing ring rail 11 and since in order to fill in at the base of the bobbin it is necessary to bring the ring rail 11 level with the bobbin at the lower end of its traverse or with the heel of the cam 40 in engagement with the roller 46, it is necessary to reverse the angle of the face 29^a of the block 28^a. To obtain this result settings for taper and length of stroke are made as before described. Then with the heel of cam 40 against roll 46 and the lever 34 in position to give the long stroke, the angle of face 29^a is adjusted parallel to or approximately parallel with face plate 39 of lever 37. With the

cam in this position, the level of the ring rail is checked on the short stroke and any correction necessary in the adjustment of the angle of block 28^a to compensate for arcuate movement of fulcrum 37^a is made and then the ring rail 11 is leveled to the base of the bobbin by means of jack screw 27. It will be seen that the mechanism shown in Fig. 4 operates on the same principle as the mechanism shown in Fig. 1.

10 It is to be understood that this builder motion may be applied to spinning, twisting or any other textile machine where it is necessary to wind this type of package and that I, therefore, do not limit the application of this invention to spinning frames only.

15 This mechanism has been thoroughly tested and has been in actual use for some time and no mechanical difficulties have been found.

It will be obvious that many changes might 20 be made in the details of this mechanism without departing from the spirit of the invention as defined in the appended claims.

What is claimed is:

25 1. In a spinning frame having a fixed rail and a movable rail, one carrying spinning rings and the other carrying spindles, a builder mechanism including a lever pivoted at one end, movement transmitting means between the free end of the lever and the movable rail, means operatively engaging directly with the middle of the lever and acting through rectilinear movement to continuously oscillate said lever, said means having a fixed stroke, and means to repeatedly shift the lever longitudinally to thus vary the distance between the fulcrum of the lever and the point of application of the said oscillating means thereto.

30 2. In a spinning frame having a fixed rail and a movable rail, one carrying spinning rings and the other carrying spindles, a builder mechanism including a lever pivoted at its lower end, movement transmitting means between the free end of the lever and the movable rail, means operatively engaging the middle of the lever and acting to continuously oscillate said lever, said means having a fixed stroke, and means for alternately raising and lowering the lever by alternately raising and lowering the pivotal fulcrum of said lever to thus vary the distance between the fulcrum and the point of application of the oscillating 35 means to the lever.

35 3. In a spinning frame having a fixed rail and a movable rail, one carrying spinning rings and the other carrying spindles, a builder mechanism including a lever pivoted at its lower end, movement transmitting means between the free end of the lever and the movable rail, means operatively engaging the middle of the lever and acting to continuously oscillate said lever, said means having a fixed stroke, and means for alternately raising and lowering the lever by alternately raising and lowering the pivotal fulcrum of said lever to thus vary the distance between the fulcrum and the point of application of the said means engaging the lever, said lever engaging means being constructed and arranged to adjustably vary the amplitude of movement of the movable rail.

40 4. In a spinning frame having a fixed rail and a movable rail, one carrying spinning rings and the other carrying spindles, a builder mechanism including a lever pivoted at its lower end, movement transmitting means between the free end of the lever and the movable rail, means operatively engaging the middle of the lever to continuously oscillate said lever, said means having a fixed stroke, a lever pivotally supported inter-

mediate its ends and at one end supporting the fulcrum for the lower end of and supporting the first named lever, and means repeatedly shifting the opposite end of the second named lever to thus vary the distance between the fulcrum of the first named lever and the point of application of the oscillating means thereto.

45 5. In a spinning frame having a fixed rail and a movable rail, one carrying spinning rings and the other carrying spindles, a builder mechanism including a lever pivoted at its lower end, movement transmitting means between the free end of the lever and the movable rail, means operatively engaging the middle of the lever to continuously oscillate said lever, said means having a fixed stroke, a lever pivotally supported between its extremities and movable in a vertical plane, one end of said last named lever supporting the fulcrum for and supporting the first named lever, and an adjustable throw crank operatively coupled with the other end of the second named lever, and means for continuously rotating said crank.

50 6. A builder mechanism, including a reciprocating chain rail, a vertically disposed lever pivotally supported at its lower end and operatively engaging the chain rail, means engaging directly with a side of said lever and having rectilinear movement thereagainst to oscillate it, and means constructed and arranged to alternately raise and lower the pivotal end of the lever with relation to the lever oscillating means.

55 7. A builder mechanism, including a reciprocating chain rail, a vertically disposed lever pivotally supported at its lower end and operatively engaging the chain rail, a continuously rotatable cam, means engaged by the cam and engaging the middle of said lever to oscillate it, said cam engaged means having rectilinear movement in the direction of lever movement and means constructed and arranged to alternately raise and lower the pivotal end of the lever with relation to the point of application of power from said cam to the lever.

60 8. A builder mechanism, including a reciprocating chain rail, a vertically disposed lever pivotally supported at its lower end and operatively engaging the chain rail, a continuously rotatable cam, means engaged by the cam and engaging the middle of said lever to oscillate it, means constructed and arranged to alternately raise and lower the pivotal end of the lever with relation to the point of application of power from said cam to the lever, said means including a lever pivoted between its ends for vertical movement and pivotally connected to the lower end of the first named lever, and means engaging said second named lever to continuously oscillate it.

65 9. A builder mechanism including a reciprocating chain rail, a slide carried thereby, a vertically disposed lever engaging at one end with the slide, a cam, operative connections between the cam and lever causing the lever to oscillate as the cam rotates, the lever having sliding engagement with the operative connections, the connections having rectilinear movement between the cam and lever and means for varying the distance between the point of application of power to the lever by said cam and the fulcrum of the lever by shifting the lever and the fulcrum.

70 10. A builder mechanism, including a reciprocating chain rail, a slide carried thereby, a member mounted on the slide and having a vertical face, a vertically disposed lever engaging at its upper end with the vertical face of said member.

- a lever pivoted intermediate its ends and at one end pivoted to the lower end of the first named lever, constantly operated cam means for oscillating said first named lever and including an element bearing at one point against the first named lever, and means for constantly oscillating the second named lever to alternately increase or diminish the distance between the fulcrum of the first named lever and point of application of power to the first named lever from said cam.
11. A builder mechanism, including a reciprocating chain rail, a slide carried thereby, a member mounted on the slide and having a vertical face, a vertically disposed lever engaging at its upper end with the vertical face of said member, a lever pivoted intermediate its ends and at one end pivoted to the lower end of the first named lever, constantly operated cam means for oscillating said first named lever and including an element bearing at one point against the first named lever, means for constantly oscillating the second named lever to alternately increase or diminish the distance between the fulcrum of the first named lever and point of application of power to the first named lever from said cam, and including an adjustable throw crank and a connecting rod between the wrist pin of said crank and the adjacent end of the second named lever.
12. A builder mechanism, including a reciprocating chain rail, a slide carried thereby, a leveling block pivotally mounted upon the slide and extending upward therefrom, means for adjustably tilting the leveling block, a lever having a roller at its upper end engaging the face of said leveling block, a second lever pivoted for movement in a vertical plane and pivotally connected at one end to the lower end of the first named lever to constitute a fulcrum therefor, means for constantly oscillating the first named lever, including a member having rolling contact with the face of the first named lever, and means for constantly oscillating the second named lever at a relatively slow speed to thus alternately increase and decrease the distance between the fulcrum of the first named lever and said point of contact with the lever oscillating means.
13. A builder mechanism, including a reciprocating chain rail, a slide carried thereby, a leveling block pivotally mounted upon the slide and extending upward therefrom, means for adjustably tilting the leveling block, a lever having a roller at its upper end engaging the face of said leveling block, a second lever pivoted for movement in a vertical plane and pivotally connected at one end to the lower end of the first named lever to constitute a fulcrum therefor, means for constantly oscillating the first named lever including a member having rolling contact with the face of the first named lever, means for constantly oscillating the second named lever at a relatively slow speed to thus alternately increase and decrease the distance between the fulcrum of the first named lever and said point of contact with the lever oscillating means, including an adjustable throw crank, a longitudinally adjustable connecting rod between the crank and the adjacent end of the second named lever, and a vertically adjustable pivot for the second named lever.
14. A builder mechanism, including a reciprocating chain rail, a slide carried thereby, a leveling block pivotally mounted upon the slide and extending upward therefrom, adjustable means for tilting the leveling block, a vertically extending lever having rolling contact at its upper end with the face of the leveling block, a longitudinally extending lever pivoted to the lower end of the vertical lever and constituting a fulcrum therefor, means for vertically adjusting the pivot upon which the second named lever rocks, a continuously driven crank, a connecting rod between the crank and the adjacent end of the second named lever, the connecting rod being longitudinally adjustable to increase or decrease its length, and means for oscillating the first named lever, including a slide, a roller engaging the adjacent face of the first named lever and having a mounting adjustable in any one of a plurality of vertical positions in said slide, and a continuously driven cam operatively engaging said slide to reciprocate it and oscillate the first named lever, the second named lever acting to slowly but continuously increase or diminish the distance between the fulcrum of the first named lever and the roller engaging the face of the first named lever.
15. A spinning frame having a fixed rail and a movable rail, one carrying spinning rings and the other carrying spindles, a builder mechanism including a chain rail, chains carried by the rail and operatively engaging the first named movable rail to raise or lower it as the chain rail is reciprocated, a leveling block operatively pivoted upon the chain rail and extending upward therefrom and having a rearwardly extending arm and a downwardly inclined face, a screw passing through said arm whereby the leveling block may be tilted to vary the inclination of its face with reference to a vertical plane, a longitudinally extending lever pivoted intermediate its ends, a vertically extending lever fulcrumed upon one extremity of the first named lever and having rolling contact at its upper end with the inclined face of said leveling block, a constantly operated cam, a slide associated therewith, a roller bearing against the adjacent face of the second named lever and having a mounting provided with a screw-threaded shank engaging said slide, and means constructed and arranged to slowly but continuously oscillate the first named lever to thus increase or diminish the distance between the fulcrum of the second named lever and point of contact of the roller therewith.
16. A builder-motion, including a reciprocating chain rail having means whereby it may be operatively connected to a builder rail, a leveling element operatively pivoted on the rail and having a work face, means for tiltably adjusting the element to bring said face into predetermined angular relation to a vertical plane, a vertically disposed lever engaging at its upper end against the face of the element and pivoted at its lower end, constantly operated means for oscillating the lever to thereby oscillate the chain rail through application of pressure through the upper end of the lever to said face, and constantly operated means for slowly and continuously increasing the throw of the lever and then decreasing said throw, said last-named means operating at a speed considerably less than the speed of said lever oscillating means.
17. A builder motion, including a reciprocating chain rail having means whereby it may be operatively connected to a vertically reciprocable builder rail, a slide mounted on the chain rail, means for adjusting the slide longitudinally on the rail, a leveling element pivoted to the slide and extending upward therefrom, means for tiltably adjusting the element to bring its face into predetermined angular relation to a vertical

plane, a vertically disposed lever engaging at its upper end with the face of said leveling element and pivoted at its lower end, constantly operated means engaging the intermediate portion of said lever to oscillate it, said means having a uniform stroke, and constantly operated means for slowly and continuously lifting the lever relative to the oscillating means and then lowering the said lever relative thereto to thus change the stroke of the free end of the lever, said last-named means operating at a speed which is a fraction of the speed of the lever oscillating means.

18. A builder motion, including a vertically movable builder rail, a chain rail having means whereby it may be operatively connected to the builder rail to reciprocate it, a body on the chain rail and having a working face, a vertically disposed lever pivotally supported at its lower end and at its upper end engaging said face, constantly operated means engaging the intermediate portion of the lever and constructed and arranged to slowly oscillate it, constantly operated means operated at a fraction of the speed of the first-named means constructed and arranged to slowly raise and lower the lever relative to its point of engagement with the lever oscillating means to thereby increase or decrease the stroke

of the lever and of the chain rail, and means constructed and arranged to cause the movable builder rail on all strokes to lower to the same point regardless of the change in the length of the stroke of the lever and chain rail.

19. A builder motion, including a vertically movable builder rail, a longitudinally reciproitable chain rail, means operatively connecting the chain rail to the builder rail to vertically reciprocate the latter, an element on the chain rail having an upwardly extending face, a vertically disposed lever pivotally supported at its lower end and at its other end engaging said face, a constantly operating cam, a slide operatively engaging said cam and engaging against the intermediate portion of the lever whereby the rotation of the cam will oscillate the lever, a longitudinally extending lever pivoted intermediate its ends and at one end pivotally supporting the lower end of said vertically disposed lever, a crank, an operative connection between the crank and that end of the longitudinally extending lever remote from the vertically extending lever, means for slowly rotating the cam, and means for rotating the crank at a fraction of the speed of the cam.
